ROCKET-PROPELLED DEVICE

Maurice H. Goehmann, Dearborn, Mich., assignor,
by mesne assignments, to United States of
America

Application December 27, 1943, Serial No. 515,653

3 Claims. (Cl. 102—49)

1

This invention relates to rocket-propelled devices, particularly to explosive projectiles and the like.

In one type of rocket projectile, the propelling charge is supported within a casing secured to the trailing end of the projectile proper, that is, the main body which carries the explosive charge. The casing, in projectiles of this type, is adapted to fragment upon the setting off of the main explosive charge and thus add to the fragmentation of the projectile. There are instances when the projectile may become lodged in the projector or when the propelling charge, when ignited, may develop a pressure within the casing which is so abnormally high as to cause the casing to burst. Such inadvertent bursting, of course, is apt to cause serious injury to those near the projector.

It has been proposed to overcome this danger of inadvertent bursting of the casing by providing a circumferentially weakened zone in the casing, the strength of which is sufficiently less than the bursting strength of the casing to permit the casing to break off from the main body of the projectile in the event an abnormal pressure is developed within the casing. The disadvantage in such an arrangement is that the projectile is of no further use unless or until a new casing is provided. Obviously this would be impractical in the field.

The primary object of the present invention is to provide projectiles of the aforesaid type with a means which will automatically limit the pressure developed in the casing to a predetermined value whereby to prevent bursting of the casing.

Another object is to provide a rocket-propelled device with a venturi which will automatically adjust itself to limit pressures developed during firing of the projectile charge to a predetermined value.

With the above and other objects in view, which will be apparent from the following detailed description to those skilled in the art, the present invention consists of certain features of construction and combinations of parts to be hereinafter described with reference to the accompanying drawing, and then claimed.

In the drawing which illustrates suitable embodiments of the present invention,

Figure 1 is longitudinal side elevation of the projectile, portions of the same being broken away to better illustrate the construction;

Figure 2 is a section taken approximately on line 2—2 of Figure 1;

Figure 3 is a transverse section taken approximately on line 3—3 of Figure 2; and

2

Figure 4 is a fragmentary view of a modified Venturi arrangement.

Referring to the accompanying drawing, the projectile comprises a main projectile body 10 having a cavity 11 for holding the explosive charge 12, and an elongated casing 13 threadedly or otherwise suitably secured to the trailing end of the body 10. The propelling charge represented by the cylindrical elements 14, is supported by a cage 15, also secured to the trailing end of the body 10 within the casing 13.

The rearward end 16 of the casing 13 is reduced in diameter and provided with an inturned radial flange 17.

The Venturi device is comprised of an outer toroidal element 18 having its inner surface suitably contoured to provide the outer wall of the Venturi passage 19, and an annular inner element 20 having its outer surface shaped to provide the inner wall of the Venturi passage. The forward end of the element 18 is provided with a coaxial sleeve-like portion 21 which is integrally connected with the inner wall of the element 18 by means of radial vanes 22 of streamlined contour.

The inner Venturi element 20 is slidably mounted on a headed rod 23 extending through the sleeve-like portion 21 and is axially urged against the portion 21 by a compression spring 24 which surrounds the rod 23, the spring abutting a split spring washer 25 carried within a circumferential groove 26 provided in the end of the rod 23.

Prior to the assembly of the casing 13 to the projectile body 10 the assembled Venturi device is slid into the reduced end 16 of the casing 13 and secured in place in any suitable manner, such as, for example, by silver brazing indicated at 27 in Figure 1.

It is to be noted that the inner Venturi element 20 is formed at its forward end with a conical wall 28 of greater angularity than the remainder, which wall 28 presents a substantial area exposed to the out-rushing gases.

The modification, shown in Figure 4 is similar to that shown in Figure 1, similar parts bearing the same numbers. The inner Venturi element 20 in this construction is of cup-shaped design to present a radial wall 29 to the out-rushing gases.

The spring 24, in the devices shown, is so calibrated that it will maintain the inner Venturi element 20 in abutting engagement with the sleeve-like portion 21 for all pressures developed within the casing 13 by the burning propelling charge 14 up to a normal pressure. However, should the developed pressures exceed this pre-

determined value, due to a faulty or improperly burning propelling charge, the increased flow of gases acting on the surface 28 in the case of the showing in Figure 1 or the surface 29 in the case of the showing in Figure 4 overcomes the resistance of the spring 24, thus increasing the area of the Venturi passage 19 and thereby effecting a drop in pressure to the normal value. The normal pressure, of course, is predetermined to be a value less than that which would cause 10 bursting of the casing 13.

There is thus provided an arrangement which is automatically effective to relieve the casing of abnormal or excessive pressure which, in the absence of such arrangement, would tend to burst 15 the casing and endanger the lives of those who might be in the vicinity of the equipment.

Obviously various changes may be made in the construction and detailed arrangement of the parts described without departing from the spirit 20 and substance of the invention, the scope of which is defined by the appended claims.

What is claimed is:

1. In a rocket-propelled device having a propelling rocket charge and a casing surrounding said charge, said casing having an open end through which the gases resulting from the burning of the charge exhaust to the atmosphere, concentric outer and inner elements disposed within said open end and being contoured to form a Venturi passage therebetween for said gases, said outer element having a coaxial portion and a coaxial rod element carried by said coaxial portion, said inner element being slidable on said rod element, and spring means urging said inner element into engagement with said coaxial portion, said spring means being adapted to maintain said engagement during the development of pressures within said casing up to a predetermined maximum value and to permit said 40 inner element to move axially and enlarge said passage upon the development of pressures above said predetermined value.

2. In a rocket-propelled device having a propelling rocket charge and a casing surrounding 45 said charge, said casing having an open end through which the gases resulting from the burning of the charge exhaust to the atmosphere, concentric outer and inner elements disposed within said open end and being contoured to form 50 a Venturi passage therebetween, for said gases, an annular member concentrically disposed within and circumferentially spaced from the inner

4
wall of said outer element and being supported therefrom, a rod element extending through and being supported by said annular member, said inner element being slidably supported on said rod element, a compression spring surrounding said rod element and having one end abutting said inner element, and stop means on said rod element engaging the other end of said spring whereby to normally engage said inner element with said annular member, said inner element being responsive to an increase in pressure in said casing beyond a predetermined value to slide on said rod against the resistance of said spring to enlarge said Venturi passage.

3. In a rocket-propelled device having a propelling rocket charge and a casing surrounding said charge, said casing having an open end through which the gases resulting from the burning of the charge exhaust to the atmosphere, a Venturi device within the open end of said casing having a Venturi passage of such restriction as to permit the propelling charge upon burning thereof to build up pressures within said casing, said Venturi device comprising inner and outer concentric elements, the inner surface of the outer element forming one wall of the Venturi passage and having entrance and outlet ends, said inner element being within the outlet end of the outer element and forming the other wall of said passage, rod means coaxially supported within the entrance end of said passage and extending through and slidably supporting said inner element, and compression spring means carried by said rod means and urging said inner element to a predetermined forward position in said passage, said inner element being effective to overcome the resistance of said spring only upon an increase in pressure within said casing beyond a predetermined maximum value.
